UNITED STATES PATENT OFFICE.

JOHN F. BARRON, OF RUMFORD FALLS, MAINE.

SCAFFOLD-HANGER.

SPECIFICATION forming part of Letters Patent No. 656,007, dated August 14, 1900.

Application filed January 4, 1900. Serial No. 354. (No model.)

To all whom it may concern:

Be it known that I, JOHN F. BARRON, a subject of the Queen of Great Britain, and a resident of Rumford Falls, in the county of Oxford and State of Maine, have invented a new and Improved Scaffold-Hanger, of which the following is a full, clear, and exact description.

The object of the invention is to provide a new and improved scaffold hanger or sling arranged to enable workmen to readily level the scaffold or platform while in use on a building and insure comfortable working and permit of ready adjustment according to the width of the platform, to securely hold the latter in place, and allow of attaching the hanger or sling at any desired point of the platform to prevent the hanger from striking against the projections on the face of the building when raising or lowering the platform.

The invention consists of novel features and parts and combinations of the same, as will be fully described hereinafter and then pointed out in the claims.

25 A practicable embodiment of the invention is represented in the accompanying drawings, forming a part of this specification, in which similar characters of reference indicate corresponding parts in all the views.

30 Figure 1 is a perspective view of the improvement as applied. Fig. 2 is an end view of the same, and Fig. 3 is an end elevation of a modified form of the improvement.

The improved scaffold hangers or slings A 35 A are alike in construction and support a scaffold or platform B of any approved construction. Each of the hangers or slings A A consists of a bottom C and sides D and E, pivotally connected with the ends of the bottom 40 and also pivotally connected at the top with an eye F, adapted to be engaged by the hook of a pulley-block G or other device used for suspending the platform from the roof of a building and for raising and lowering it in the usual manner. The bottom C of each hanger or sling is made in two sections C' C², connected with each other at their adjacent threaded ends by a turnbuckle C³ to permit the user to lengthen or shorten the bottom, according to the width of the platform or scaffold B, so that the longitudinal beams

B' thereof are clamped between the upturned ends C⁴ C⁵ of the sections C' C², respectively, to securely hold the platform in place on the corresponding hanger or sling. 55

As shown in Fig. 2, the sections C' C² may be provided near their outer ends with the drops C⁶ to bring the turnbuckle C³ below the under side of the platform B to allow the operator to conveniently turn the turnbuckle, 60 and make the desired adjustment without interfering with the platform B. The sections may, however, be straight, as shown in the sling C⁷, (illustrated in Fig. 3,) in which the sections C⁸ are without the drops C⁶, but are 65 connected with each other by the turnbuckle C⁹. In this case the beams B' of the platform have their lower edges a suitable distance below the platform-bottom, so that the turnbuckle C⁹ can be turned without interfering with the bottom of the platform. 70

The outer side E of the hanger or sling is also made in sections E' E², connected with each other by a turnbuckle E³, so that the operator can readily lengthen or shorten this side 75 by turning the turnbuckle E³ accordingly to permit the operator to readily level the platform when it is suspended from a building, and thereby insure a comfortable stand for the workmen while using the platform to accomplish the desired work on the building. 80

The lower ends of the sides D and E are pivotally connected with the upturned ends C⁴ C⁵, and the upper ends of said sides are pivotally connected with separate eyes F' on the 85 eye F, the eyes F' forming a recess F² at the bottom of the main eye F to permit of bringing the pulling or loose end of the rope around in the recess F² to allow of quickly and easily hitching the pulling end of the rope by giving the rope a half-twist to form a loop, which latter is then hooked onto the hook of the pulley-block. By this arrangement the rope end is securely held in place and without danger of being unhitched. 90

95 By the arrangement described the hangers or slings can be readily moved to any desired point in the length of the platform or scaffold B, and the hangers are completely independent of the cross-beams of the platform. Furthermore, the operator on the platform while the same is in use on a building can at any 100

time readily lengthen or shorten the sides E, so as to bring the platform B into a horizontal position for the purpose mentioned.

Having thus fully described my invention, 5 I claim as new and desire to secure by Letters Patent—

1. A scaffold-hanger, comprising a bottom, consisting of adjustable sections and sides hinged to the bottom and pivotally connected 10 with each other at their ends, one of the sides being arranged to be lengthened or shortened, substantially as shown and described.

2. A scaffold-hanger having a bottom with sections adjustable one upon the other, to allow of lengthening or shortening the bottom, the ends of the bottom being turned up to form clamping-lugs for engagement with the longitudinal scaffold-beams, substantially as shown and described.

20 3. A scaffold-hanger having a bottom formed of sections connected with each other by a turnbuckle, the ends of the sections being turned up to form clamping-lugs for engagement with the longitudinal scaffold-beams, substantially as shown and described.

25 4. A scaffold-hanger having a bottom formed of sections connected with each other by a turnbuckle, the ends of the sections being turned up to form clamping-lugs for engage-

ment with the longitudinal scaffold-beams, 30 said sections also having drops near their inner ends for bringing the turnbuckle below the bottom of the scaffold, substantially as shown and described.

5. A scaffold-hanger, comprising a bottom 35 made in sections to permit of lengthening or shortening the bottom, the latter having upturned ends for clamping the longitudinal beams of the scaffold, sides pivotally connected with the upturned ends of the bottom, 40 one of the sides being made in sections connected with each other by a turnbuckle, and eyes independently engaged by the upper ends of said sides, substantially as shown and described. 45

6. A scaffold-hanger, comprising a bottom portion and side portions, and an eye-plate having eyes for receiving the ends of the side portions and having an eye to receive a hook, and also having a recess between the first- 50 named eyes, for the purpose described.

In testimony whereof I have signed my name to this specification in the presence of two subscribing witnesses.

JOHN F. BARRON.
